UNITED STATES PATENT OFFICE.

GEORGE B. ROBINSON, OF DERBY, CONNECTICUT.

DESIGN FOR CARRIAGE-SPRING.

Specification forming part of Design No. 5,051, dated June 27, 1871.

To all whom it may concern:

Be it known that I, GEORGE B. ROBINSON, of Derby, in the county of New Haven and State of Connecticut, have invented a new and original Design for a Carriage-Spring; and I do hereby declare that the following is a full, clear, and exact description thereof, which will enable others skilled in the art to make and use the same, reference being had to the accompanying drawing forming part of this specification.

The drawing represents a perspective view of my new design for a carriage-spring.

My invention consists in a new design for carriage-springs, as hereinafter fully described and subsequently pointed out in the claim.

A B in the drawing are the two leaves of the spring. They are connected at the ends in suit-

able manner, and are made of tapering form, to be thick at the middle and thin at the ends, as shown. This is a new form of spring, producing useful results, as it combines strength at the loaded parts with elasticity near the joints. *a b* are prismatic pins projecting from the faces of the leaves, to constitute the connection with the supporting and supported frames, in place of the straps heretofore used.

I claim as my invention—

The leaves A B, with pins *a b* projecting from the faces thereof, as a new design in carriage-springs.

GEORGE B. ROBINSON.
